UNITED STATES PATENT OFFICE.

HARRY B. NAYLOR, OF PITTSBURGH, PENNSYLVANIA, ASSIGNOR TO NATIONAL FIRE PROOFING COMPANY, OF PITTSBURGH, PENNSYLVANIA, A CORPORATION OF PENNSYLVANIA.

TILE STRUCTURE AND TILE THEREFOR.

1,261,426.

Specification of Letters Patent.

Patented Apr. 2, 1918.

Application filed March 31, 1915. Serial No. 18,258.

To all whom it may concern:

Be it known that I, HARRY B. NAYLOR, a citizen of the United States, residing at Pittsburgh, in the county of Allegheny and 5 State of Pennsylvania, have invented a new and useful Improvement in Tile Structures and Tiles Therefor, of which the following is a full, clear, and exact description, reference being had to the accompanying drawings, forming part of this specification, in which—

Figure 1 is a transverse section of a sewer constructed in accordance with my invention;

Fig. 2 is a view partly in side elevation and partly in vertical section, the section being on the line II—II of Fig. 1;

Fig. 3 is an enlarged sectional view of the lower part of the structure showing a modified form of tile;

Fig. 4 is a perspective view of one of the tiles of Fig. 3;

Fig. 5 is a fragmentary end view showing the joint between two adjacent tiles of 25 Figs. 1 and 2;

Fig. 6 is an end view of one of the tiles of Figs. 1 and 2; and

Fig. 7 is a view partly in side elevation and partly in vertical section of two adjacent tiles of the form shown in Figs. 1 and 2.

My invention has relation to hollow tile structures, and more particularly to sewers and other conduits of elliptical or ovoidal form in cross section.

35 The object of my invention is to provide a structure of this character which will possess a maximum strength, in which the joints are well bonded, and which can be readily and rapidly built. A further object of the invention is to provide a terracotta tile, especially adapted to structures of this type.

The nature of my invention will be best understood by reference to the accompanying 45 drawings, in which I have shown the preferred embodiment thereof and which will now be described, it being premised, however, that various changes may be made in the details of construction and arrangement of the parts, without departing from the spirit and scope of my invention as defined in the appended claims.

Referring first to the form of tile shown in Figs. 1, 2, 5, 6 and 7, each tile of which 55 the structure is composed, and which is

formed of burnt terracotta, consists of an outer wall 2, side walls 3 and 4, an inner wall 5, and a radial web 6, which divides the interior of the tile into the two large cells 7. The outer wall 2 of each tile is of 60 convex form, while the inner wall 5 is of concave form, the radii of curvature of these two walls being different at different parts of the structure. The side wall 3 is of reentrant angular form, while the opposite side wall 4 is of convex angular form, being adapted to fit within the reentrant recess side 3 of an adjacent tile. The inner wall 5 is of a total thickness considerably greater than that of the outer wall 2, but 65 is formed of a plurality of small cells 8, which are separated from each other by the webs 9. Both the large cells 7 and the small cells 8 extend longitudinally through the tile from end to end.

75 The side 3 of each tile is also formed with a longitudinal projection 10, which forms an extension of a portion of the inner wall 5; and the opposite side 4 has an undercut projection 11 of corresponding form, so that 80 when the tiles are in place, an overlap will be formed at each of these projections as well as at the reentrant recess side. One end of each tile has a curved recess 12, and at the opposite end has a corresponding projection 13, adapted to seat in the recess of the adjacent tile. Preferably, the cells 8 are so placed that a portion of each cell is 85 in the projection 13 and recess 12.

In building up the structure, it is formed 90 entirely of tiles of the above description, except at its extreme lower portion. This requires the use of a central base tile 14, which is also of hollow form with a flat base 15, large internal longitudinal cells 16 95 and a plurality of longitudinal cells 17, similar to the cells 8. The inner wall 18 of this tile has its ends constructed similarly to the ends of the tiles first described, but has an edge projection 19 at each edge. Placed at 100 either side of the tile 14 are two specially shaped tiles 20, which are similar to each other. These tiles have the flat bases 21, the internal large cells 22, and the smaller cells 23. Interposed between each tile 20 105 and the adjacent tile of the body of the structure is another special tile 24, having a single large cell 25 and small cells 26. One of the tiles 24 has its upper face of 110 convex angular form, as shown, correspond-

ing to the convex side of the adjacent body tile; and the other has a concave upper face, corresponding to the adjacent convex face of the adjacent body tile. It also has a recess 11^a, to receive the projection 10 of the adjacent body tile, and at the opposite side a projection 27, to fit in the recess 28 of the tile 20. Adjacent tiles are separated from each other by continuous longitudinal courses 29 of mortar or cement.

10 It will be seen from an examination of Fig. 1 that the structure is an exceedingly strong one, the upper part being a perfect arch, while the sides of a different radius are well adapted to receive the thrusts of and support this arch. Strains exerted upon the structure in any direction instead of tending to separate the tiles and open the joints between them act to close these joints.

15 20 The intervening projections 10 and recesses 11, especially when combined with the intervening faces of the tiles give a very strong keying action. The side contour of the tiles also results in a more or less irregular non-radial joint, well adapted to resist leakage. The provision of the projections 13 and the undercuts 12 in connection with the plurality of small longitudinal cells 8 is also a feature of importance. In

25 30 building up the structure, after one course of tiles has been laid, the ends of the tiles are covered with cement or mortar before the end-abutting tiles of the next course are put in place. In other generally similar structures with which I am familiar, when the next course of tiles are pushed endwise into place, a very considerable portion of the cement or mortar will be crowded upwardly and outwardly into the ends of the large 35 cells, and there will not be a proper amount of mortar left at this point. By providing the plurality of small cells 8, with their intervening webs 9, these webs will act to cut the mortar at this point, so that instead of it being crowded bodily outward, small portions thereof will be forced into the ends of the adjacent small cells 8 in the manner 40 shown at 13^b in Fig. 7. This insures a proper and well-bonded mortar joint, adjacent the inner surface of the conduit and retains the 45 mortar in position.

50 The modification shown in Figs. 3 and 4 is intended for large conduit structures having a greater wall thickness. The general 55 construction and arrangement is the same as that described, except that the body tiles 30 are made of greater radial thickness and instead of having two large longitudinal cells are shown as having six of these cells,

designated 31, and separated by the internal 60 webs 32. The special tiles 14^a, 20^a and 24^a at the bottom of the structure correspond, respectively, to special tiles 14, 20 and 24 of Fig. 1 and are, in general of similar form to the latter, but are of larger dimensions 65 and have a greater number of internal large cells. The central tile 14^a is provided with a concave or trough-shaped inner surface 14^b. The recess formed by this trough extends beyond the radius of the inner curved 70 wall of the interior of the structure, and forms a sub-conduit, which will collect and form a flow channel for the liquid in the conduit when such liquid is present in small 75 volume. This insures a constant and regular flow of the sewerage or other liquid, notwithstanding a very small volume thereof, and prevents the collection and stagnation which occurs when it is distributed to a greater or less extent over the bottom of the 80 conduit, as in the usual construction. The exact form and arrangement of these cells may be considerably varied from that shown. In general, the arrangement of the interior webbing is such as to make all the cells of 85 substantially uniform thickness, the purpose of this being to facilitate the manufacture.

My invention provides means whereby 90 sewers and other similar conduits of elliptical or ovoidal cross section and of great strength and durability may be constructed from terracotta tiles.

I claim:

A hollow tile having inner and outer 95 parallel walls united at one edge by an angular reentrant side wall and at the other edge by an angular convex side wall, there being a plurality of comparatively large 100 openings between said walls and a plurality of comparatively small longitudinal openings extending through the inner wall, the one end of the tile having a convex projecting portion, and a straight portion at each side of the convex portion, the other end 105 having a concave recess and a straight portion at each side of the recess, the small 110 openings passing through one of the straight portions and the recessed portion at one end, and one of the straight portions and the projecting portion at the other end; substantially as described.

In testimony whereof, I have hereunto set my hand.

HARRY B. NAYLOR.
